UNITED STATES PATENT OFFICE.

BENJAMIN BLACHER, OF PROVIDENCE, RHODE ISLAND, ASSIGNOR TO BLACHER BROTHERS, A PARTNERSHIP COMPOSED OF BENJAMIN BLACHER AND HARRY BLACHER, OF PROVIDENCE, RHODE ISLAND.

FASTENER FOR BAG FRAMES.

Application filed July 9, 1927. Serial No. 204,605.

This invention relates to clasps or fasteners for the frames of bags, purses or similar articles and consists of improvements in the construction and method of operation of the 5 same.

A principal object of the invention is to provide a device of the type specified which is simple in construction, neat and ornamental in appearance, and efficient in use for securely 10 clasping the frame-members of the bag to prevent unwarranted or accidental opening thereof.

Another object of the invention is to provide a bag fastener or clasp which is economical 15 to manufacture and convenient to assemble on practically all types of bag frames.

Another object of the invention is to provide a device of the type specified which is particularly strong and rugged in construction 20 and proof against derangement or getting out of order.

Further objects of the improvement are set forth in the following specification which describes a preferred embodiment of the invention 25 as illustrated in the accompanying drawings. In the drawings:

Fig. 1 is a view showing a conventional type of hand-bag having its hinged frame-members provided with the present improved 30 clasp or fastening-means;

Fig. 2 is an end view of the same;

Fig. 3 is a side view of a portion of the bag frame showing the clasp or fastener in opened or released position; and

Fig. 4 is an enlarged cross-sectional view 35 of the frame and its fastening device, taken on line 4-4 of Fig. 1.

Referring to the drawings, Figs. 1 and 2 illustrate a usual style of hand-bag or purse 40 comprising a pouch 2, of leather or other flexible material, having its mouth closed by mating frame-members 3 and 4. The frame-members 3 and 4 are generally constructed of sheet-metal of channel shape in cross-section, as shown in Fig. 4 of the drawings, and their terminal portions are hinged together by suitable means such as the rivets 5 illustrated in Fig. 2.

In accordance with a preferred form of 50 construction of the present invention, my improved clasp or fastening-device comprises, essentially, a slide 7 slidable along the top of one frame-member 3 and engageable over a

narrow lip or lug 8 projecting from the top 55 of the other member 4.

The slide 7 may be constructed of any suitable shape and as herein shown consists of a rectangular block having a setting 9 on its top for mounting a jewel or ornament 10 which embellishes its appearance. The slide 7 is bored longitudinally to provide a bearing 11 for a horizontal rod 12 which serves as a guide or track on which the slide slides. The rod 12 may be mounted on the top of the bag frame in any suitable manner and, as herein shown, it is held at its ends in standards or posts 15 secured to the frame-member 3. The posts 15 are preferably of ornamental design and may comprise balls having flanged standards which are soldered or riveted to the top of the member 3. The ends of the rod 12 are received in holes 16 in the posts 15 and may be riveted over to hold the rod in parallel spaced relation with respect to the top of the frame after the slide 7 has been placed thereon. 70

On the opposite complementary frame-member 4 is the flat lug or lip 8, previously referred to, which is soldered or riveted thereto to project from the top thereof. At one end of the lug 8 is an upstanding projection or abutment 18 which acts as a stop to limit the sliding movement of the slide 7 in the manner and for the purpose as hereinafter explained. As shown in Fig. 4, the under side 85 of the slide 7 is formed with a relatively narrow longitudinal slot or groove 20 adapted to engage over and enclose the sides of the lug 8 when the slide is moved to the left along its guide 12. The end of the slot 20 is cut away 90 or beveled off at 24 to adapt the stop 18 to fit thereinto to be covered by the slide when the latter brings up thereagainst.

The slide 7 is preferably formed or provided on one side with a depending ear or flange 21 which abuts the side of the frame-member 3 and thus acts to hold the slide from rocking or canting on the rod 12. On the under side of the slide 7 is a small bore 22 forming a pocket for holding a helical spring 23. The spring 23 encloses the stem of a headed pin 25 and acts to force the latter down 95 against the top of the frame-member 3 to cause it to bear frictionally thereon, thereby tending to resist the sliding motion of the 105 slide.

Having now described the construction of a preferred embodiment of the invention in detail, its method of operation will next be explained. With the slide 7 pushed to the right as shown in Fig. 3 its slot 20 is free of the lip or lug 8 on the frame-member 3 so that the two opposite frame-members may be swung apart on their hinges 5 to open the mouth of the bag. After the frame-members 3 and 4 have been brought into closed relation as shown in Fig. 2 they are clasped or fastened together at the top by sliding the slide 7 to the left, or into central position on its rod 12 as illustrated in Fig. 1. As the slide 7 is carried into this position its groove 20 will engage over the lip or lug 8 and thereby effectually clasp the two frame-members 3 and 4 in closed relation with their sides abutting as shown in Fig. 4. As before noted, the end of the slide 7 brings up against the projection or stop 18 to limit its sliding movement in fastening the clasp, and the spring-pressed pin or plunger 25 exerts a frictional resistance to its movement in the opposite direction whereby to prevent its accidental or unwarranted release.

It will be observed from the above that my invention provides a simple and efficient device for the purpose specified which may be manufactured at relatively low cost and which is adapted for use with practically all types of bag frames. The slide or clasp and its supporting rod or guide enhances the ornamental appearance of the bag or other article while at the same time providing a particularly sturdy and reliable device for the purpose specified. The clasping-means is adapted for easy and convenient operation both in opening the bag and fastening its frame-members in closed relation, and provides added security in that the clasp is proof against accidental or unwarranted release due to its frictional detent-means.

While I have herein described and illustrated a preferred form of construction of the device various modifications may be made in the design and arrangement of its parts without departing from the spirit or scope of the invention as defined in the appended claims. Therefore, without limitation in this respect, I claim:

1. In a clasp or fastening-device for bag frames or the like having opposite mating members, the combination of a guide extending longitudinally above the top of one member, a lug projecting vertically from the top of the other member, and a slide slidable on the guide and formed with a slot for engaging the opposite sides of the lug to secure the two members in closed relation.

2. In a device of the type specified the combination of complementary frame-members, a rod supported in parallel spaced relation

with respect to one member, a lug projecting from the other member, and a slide slidable on the rod and provided with means on its under side for engaging the opposite sides of the lug to clasp the two members in closed relation.

3. In a device of the type specified the combination of opposite complementary frame-members, a guide extending longitudinally of one member, a relatively flat lug projecting vertically from the other member, a slide slidable on the guide and provided with means for engaging across the opposite sides of the lug to clasp the two members in closed relation, and friction-means for resisting the sliding movement of the slide to prevent unwarranted or accidental release thereof.

4. In a device of the type specified the combination of a bag frame having opposite complementary members, a guide extending longitudinally of the top of one of said members, a lug projecting from the top of the other member, a slide slidable along the guide and formed with a slot adapted to engage the opposite sides of the lug to clasp the two members in closed relation, and resilient-means on the slide adapted to frictionally engage the top of the frame-member to resist the sliding movement of the slide to prevent unwarranted or accidental release thereof.

5. In a device of the type specified the combination of opposite complementary frame-members, a guide extending longitudinally of one member, a lug projecting from the top of the other member, a slide slidable on the guide and formed with a slot in its under side adapted to engage with the lug to clasp the two members in closed relation, a plunger on the under side of the slide, and a spring acting to press the plunger against the top of the frame-member to frictionally resist the sliding movement of the slide to prevent unwarranted or accidental release thereof.

6. In a device of the type specified the combination of opposite complementary frame-members, standards projecting from the top of one member, a rod extending between said standards in parallel relation with the top of the member, a lug projecting from the top of the other member, a slide formed with a bearing for the rod to adapt it to slide thereon and having a depending flange abutting the side of the frame-member, said slide formed with a groove on its under side adapted to engage over the lug on the other frame-member to clasp the two members in closed relation, and frictional means for resisting the sliding movement of the slide.

In testimony whereof I hereunto affix my signature.

BENJAMIN BLACHER.
